UNITED STATES PATENT OFFICE.

MATIE C. MESSLER, OF PROVIDENCE, RHODE ISLAND, ASSIGNOR TO MADGE MESSLER,
OF PROVIDENCE, RHODE ISLAND.

ARCH-SUPPORTING DEVICE FOR BOOTS AND SHOES.

Application filed May 7, 1926. Serial No. 107,374.

This invention relates to an arch-supporting device for use in boots and shoes. The invention has for its object to provide a simple and efficient device, which is capable of 5 cushioning the heel of the foot and of being automatically arched in the act of walking so as to support the arch of the foot, as will be described.

To this end, the arch-supporting device is 10 provided with a cushioning member of relatively soft rubber of substantial thickness, and preferably crepe or spongy rubber, and a flexible backing member of fibrous material to which the rubber flexible member is cemented or otherwise firmly affixed.

The flexible backing member is located in the boot or shoe so as to extend from the heel portion to the ball portion thereof, and is anchored at its front end against movement 20 in the shoe while its heel and body portion and the cushioning member affixed thereto are free to be moved longitudinally in the shoe toward and from the anchored end.

The flexible backing member may form 25 an integral part of an insole or it may be separate therefrom and cemented or otherwise attached thereto, as will be described.

The particular features of the invention 30 will be pointed out in the claims at the end of this specification.

Fig. 1 is a side elevation with parts broken away of a shoe provided with an arch-supporting device embodying the invention, and shown in its normal or substantially flat position;

Fig. 2, a like view showing the arch-supporting member in the position it assumes when the wearer of the shoe is walking, the heel portion of the cushioning member being 40 compressed and the body portion arched to support the arch of the foot;

Fig. 3, a plan, and

Fig. 4, a side elevation of a modified form of the invention.

Referring to Figs. 1 and 2, 10 represents 45 the cushioning member of the improved arch-supporting device, and 12, the backing member of fibrous material to which the cushioning member 10 is cemented or otherwise affixed.

In Figs. 1 and 2, the backing member 12 is shown as an integral part of an insole *c* of a shoe *d*, and is formed by splitting the insole *c* horizontally for a portion of its 50 length, viz: from the rear or heel portion to

the ball portion, whereby the insole is provided with an unsplit fore part 13 from which extends a lower split 14 and an upper split which forms the backing member 12. The fore part 13 and the lower split 14 constitute 60 the insole of the shoe to which the upper is stitched in the usual manner. The upper split or backing member 10 is anchored at its front end to the fore part 13 of the insole but is otherwise free from the upper and insole proper, so that it can be moved up 65 and down and also lengthwise.

The cushioning member 10 is preferably 70 made of spongy or crepe rubber and for the greater portion of its length is made of substantial thickness and is provided with a substantially wedge-shaped or tapering front portion 15, which extends to or substantially 75 to the point where the backing member 12 joins with the lower split 14.

When the weight of the wearer is off the cushioning member, the latter and its backing member 12 assume a substantially flat or horizontal position, after the manner represented in Fig. 1, and at such time, the front 80 portions of these parts are lowered from the arch of the foot.

When, however, the weight of the wearer 85 is imposed on the cushioning member, the heel of the foot compresses the rear portion of the cushioning member and forces the front portion of the cushioning member forward, and because the front end of the cushioning member is anchored, the portion between the anchored front end and the heel 90 is arched upwardly under the arch of the foot to support the latter.

This arching of the cushioning member is 95 pronounced when the wearer is walking, for in the act of walking the rear portion of the heel first strikes the ground and compresses the cushioning member and as the foot is lowered to bring the ball portion into contact with the ground, the cushioning member 10 and its backing member 12 are moved forward in the direction of the length of the shoe, and as the cushioning member and its backing member are anchored at their front ends, they are unable to be moved forward bodily, and consequently are arched upwardly 100 under the arch of the foot and into contact therewith, so as to afford a yieldable support for said arch.

When the foot is lifted from the ground, 105 the weight is removed from the cushioning 110

device and the latter is free to return to its normal or substantially flat or straight condition illustrated in Fig. 1.

It will thus be seen that the arch-supporting device is anchored at its front end, but is otherwise free to move lengthwise in the shoe, and is automatically transformed from a substantially flat condition into an arched condition to support the arch of the foot when the weight of the wearer is placed upon the cushioning member both when the wearer is standing still and when walking.

In Figs. 1 and 2, the cushioning member is anchored at its front end by securing it to a backing member which constitutes the upper layer or member of a split insole, but it is not desired to limit the invention in this respect as the backing member 12 may be cemented or stitched to the ball portion of an unsplit insole as represented in Figs. 3 and 4.

When made as shown in Figs. 3 and 4, the front end of the backing member is skived or rendered thin and may be secured to the insole *c* by cement, represented by the heavy black line 21 or by stitches 22 or by both.

When made as shown in Figs. 3 and 4, the insole *c* may be a relatively thin insole, such as now commonly used in boots and shoes, and to which the upper of the shoe is sewed, or the insole *c* and its attached arch-supporting device may be separate from the shoe and inserted therein after the manner of a slip inner sole, so that the arch-supporting member 35 may be used with different shoes of the wearer.

When the insole is insertible in the shoe, it is made of the proper size to fit somewhat snugly in the shoe so as to prevent movement thereof lengthwise of the shoe in the act of walking, and thereby enable the full benefit of the arch-supporting member to be obtained.

From the above description, it will be seen that a shoe provided with the improved arch-supporter has a cushioning member anchored at its front end at or near the ball portion of the shoe and free at its rear end to be moved longitudinally and automatically arched in the act of walking, so as to support

the arch of the foot longitudinally and transversely.

What is claimed is:

1. The combination with a boot or shoe provided with a split insole having its lower 55 split portion sewed to the upper of the shoe and having its upper split portion anchored at its front end to the fore part near the ball of the shoe and having its rear portion free from the lower split portion to move lengthwise of the shoe, of a cushioning member 60 affixed to said upper split portion to move as one piece therewith and capable of being arched.

2. In a boot or shoe, in combination, an 65 insole, an arch-support affixed to said insole and comprising a flexible back member anchored at its front end to said insole at or near the ball portion thereof and having its remaining portion free to move longitudinally with relation to said insole, and a cushioning member affixed to said backing member to move therewith.

3. In a boot or shoe, in combination, an 75 insole, and an arch-supporting device having a cushioning member of substantial thickness anchored at its front end to the ball portion of said insole and extended to the rear or heel portion of the insole and disconnected from said insole from said anchored front 80 end to said heel portion to be capable of being moved lengthwise of said insole.

4. The combination with an insole, of a fibrous member extended from the heel to near the ball of said insole and anchored to the insole at its front end while leaving its remaining portion unanchored, and a layer of relatively soft rubber affixed to said fibrous member and capable of moving with said fibrous member lengthwise of the insole. 90

5. The combination with a boot or shoe, of an arch-supporting member of relatively soft rubber located in said shoe and having its front end restrained from movement lengthwise of said shoe and having the remainder 95 of its length unrestrained to permit it to be arched.

In testimony whereof, I have signed my name to this specification.

MATIE C. MESSLER.
